PEN AND FOUNTAIN ATTACHMENT
THEREFOR

Russell E. Scott, Laurel Springs, N. J., assignor to
The Esterbrook Steel Pen Manufacturing Co.,
Camden, N. J., a corporation of New Jersey

Application September 25, 1943, Serial No. 503,809

4. Claims. (Cl. 120—114)

My invention relates to pens for lettering, drawing, and the like, and to fountain attachments therefor.

More particularly my invention relates to those pens of the lettering type having broad nibs, or those having paper-engaging writing tables usually set diagonally with respect to the longitudinal axis of the pen and which are of various shapes and sizes.

In view of the character of the ink with which pens of this type are employed, it is necessary to clean the fountain and/or the pen at more or less frequent intervals. With fountain attachments which are fixed to the pen, as many of them are, it is somewhat difficult to clean the pens and the attachments; particularly those fountains which are in the nature of a blade overlying the nib portion of the pen. Additionally, there is some danger of displacing the forward part of the fountain with respect to the writing end of the pen during a cleaning operation.

The particular feature of my invention is to provide a form of detachable or displaceable fountain that may be snapped into position with respect to the pen, and which may be readily displaced or removed from the pen for a cleaning operation. In carrying out this feature of my invention I may provide a fountain attachment wholly removable from the pen for a cleaning operation, or I may pivot or hinge the fountain attachment at one side of the pen body so that it may be swung out of position with respect to the nib portion of the pen when it is desired to clean the pen and the fountain.

The fountain attachment forming the subject of my invention includes a blade overlying the pen nibs and a clamping band which may be integral with the blade partially encircling the body of the pen intermediate its ends. In one arrangement of my invention, this clamping band has a reversely bent portion adapted to engage one edge of the pen body; the latter being preferably notched so that when the clamping band is in place, the fountain will be properly positioned with respect to the nib portion of the pen, while in the other arrangement of my invention the clamping band of the fountain may be pivotally connected or hinged to the body of the pen longitudinally of the same at one side thereof and in the same relation as the first mentioned form; the pen being notched at the side adjacent such pivotal connection in the same manner as in the first arrangement referred to.

At the opposite side of the semi-encircling clamping band, the free end is bent to form a

spring catch that will snap into engagement with the edge of the pen body and hold the attachment firmly in place, with the forward end of the same disposed in proper relation with respect to the writing table or other paper-engaging portion at the forward end of the nibs. The catch is of the same character in both forms of my improved fountain attachment.

A further feature of my invention is the stiffening or reinforcing of the fountain structure—particularly the connection between the blade and the clamping band—with a view of avoiding possible distortion of the parts of the same when placing it upon or removing it from the pen.

These and other features of my invention are more fully set forth hereinafter; reference being had to the accompanying drawing, more or less diagrammatic in character, in which:

Figure 1 is a plan view, on an enlarged scale, of one form of pen of the type to which my invention relates, with a fountain attachment within the scope of my invention applied thereto.

Fig. 2 is a side elevation of the pen and fountain attachment shown in Fig. 1.

Fig. 3 is a cross-sectional view, further enlarged, taken on the line III—III, Fig. 2.

Fig. 4 is a cross-sectional view, similar to Fig. 3, illustrating the pivotal type of structure.

Figs. 5 and 6 are fragmentary views illustrating details of my invention.

Fig. 7 is a plan view, on the same scale as Fig. 1, of a fountain attachment embodying a further feature of my invention, and

Fig. 8 is a cross-sectional view on the line VIII—VIII, Fig. 7.

My improved construction is of a simple and inexpensive character and, by reason of complete separation or displacement of the fountain with respect to the nib portion of the pen, it is most easy to clean the respective parts.

In the drawing, 10 represents one form of lettering pen with which my improved fountain attachment may be employed; such pen having a nib portion 11 which, in the present instance, has a turned-up writing table 12, and a shank portion, indicated at 13. This pen may be any form of those pens familiarly known as "lettering" pens and it will be understood that other types of pens with or without turned-up writing tables—those, for instance, with broad nib ends—are susceptible of receiving the improved fountain attachment which forms the subject of my invention.

As illustrated in Figs. 1 and 2, my improved fountain attachment may comprise a blade 15

overlying the nib portion of the pen with a forward portion of the same taper or contour as the pen and having a rounded end 16 adjacent to the writing end thereof—in the present instance, the diagonally disposed writing table 12.

The blade 15 extends rearwardly of the nib portion of the pen and is spaced from the same in the manner indicated; the forward end 16 being substantially in engagement with the nibs behind the writing table, while the rear portion of the blade is spaced some distance from the upper surface of the pen. Continuous with the blade is a neck portion 17, and this is bent downwardly with respect to the pen and joins a substantially semi-circular clamping band 18 which partially embraces the body of the pen.

The clamping band 18, shown in Figs. 1, 2 and 3, is detachably connected with the pen and for this purpose one end of the same is bent back upon itself for the desired extent, as indicated at 19, and this portion is arranged to engage a notched portion 20 at one side of the pen body (see Fig. 5) so that the blade may be properly positioned lengthwise of the pen with respect to the nib portion thereof. The opposite end of the clamping band 18 is bent to form a spring catch 21, which engages the edge of the pen body directly opposite the notched portion of the same. To provide the desired spring effect the clamping band may be arranged initially so as to be slightly smaller than the pen body or rather to be bent inwardly slightly at its free end so that when snapped over the edge of the pen body it will have the effect of a spring and be firmly held to the same. The catch may extend a slight distance below the edge of the pen body, as indicated in the drawing.

In the form of structure illustrated in Fig. 4, the clamping band 18^a is pivotally connected or hinged to the pen body, longitudinally of the same, and this may be effected by longitudinally notching the pen body, as indicated at 20^a and, in addition to such notching, longitudinally slotting the side of the pen body, as indicated at 22 (see Fig. 6). In lieu of bending one end of the clamping band to engage the notched side edge of the pen in the manner illustrated in Fig. 3, such end portion is shaped as indicated at 19^a, Fig. 4, to pass through the slot 22 and form a hinge or pivotal connection with the pen. In Fig. 4 I have illustrated by dotted lines the position of the fountain attachment when it is displaced for a cleaning operation; the broken line x indicating the contour when it is in engagement with the pen. In the arrangement shown in Figs. 1, 2 and 3, the fountain attachment is wholly removed from the pen for a cleaning operation.

Fountain attachments of the type of my invention are quite small; the metal of the same is quite thin and, by reason of the reduced neck portion between the blade and the clamping band, require more or less careful handling to avoid displacement or derangement of the parts when applying or removing the same from the pen. With a view of stiffening or reinforcing the fountain—particularly the neck portion of the same—I may displace a portion of the metal of the fountain longitudinally thereof in the form of a rib or ridge, indicated at 25, Figs. 7 and 8. While I have

shown this rib as semi-circular in cross-section, it will be understood that it may have a different contour—in the form of an inverted V, for instance, or other shape.

From the foregoing description it will be seen that I have provided a very simple and efficient form of fountain attachment for pens of the character described; that it may be readily removed or displaced for the purpose of cleaning the parts, and that when replaced it will occupy the proper position with respect to the nib portion of the pen; serving as a reservoir for the storage of a supply of ink and feeding the same in a proper manner to the pen.

My improved device may be readily snapped into position and as readily displaced or removed by operating the catch 21.

While I have described and have shown in the drawing certain specific embodiments of my invention, I do not wish to be limited to such constructions since modifications may be made in the same without departing from the spirit of my invention; all of which is deemed to be within the scope of the appended claims.

25 I claim:

1. The combination with a pen of the class described, of a snap-on fountain attachment therefor comprising a flat blade overlying the nib portion of the pen, in an inclined position, a clamping band fitting the body of the pen intermediate its ends, and a narrow neck angularly disposed connecting the blade and band; said band having a relatively wide bent-up portion in engagement with one edge of the pen and a catch in engagement with the opposite edge of the pen.

2. The combination with a pen of the class described, of a snap-on fountain attachment therefor comprising a flat blade overlying the nib portion of the pen in an inclined position, a clamping band fitting the body of the pen intermediate its ends, a narrow neck angularly disposed connecting the blade and clamping band; said band having a bent-up portion in engagement with one edge of the pen and a catch in engagement with the opposite edge of the pen, and a raised rib with tapering ends substantially centrally disposed and extending from the blade to the band and including the angularly disposed neck portion of the attachment.

3. A fountain attachment for pens comprising a flat blade disposed in an inclined position, a clamping member for embracing the body of the pen, a narrow neck angularly disposed connecting said parts; and a raised rib substantially centrally disposed extending from the blade to the clamping band and including the angularly disposed neck portion of the attachment.

4. A fountain attachment for pens comprising a flat blade arranged to overlie the nib portion of the pen in an inclined position, a clamping band, a narrow neck portion angularly disposed connecting the blade and clamping band, and a raised rib arcuate in cross-sectional contour substantially centrally disposed extending from the blade to the clamping band and including the angularly disposed neck portion of the attachment.

RUSSELL E. SCOTT.
